COLUMBIA PLANOGRAPH CO., WASHINGTON, D. C.

UNITED STATES PATENT OFFICE.

OTTO BANNER, OF EASTON, PENNSYLVANIA, ASSIGNOR TO INGERSOLL-RAND COMPANY, OF NEW YORK, N. Y., A CORPORATION OF NEW JERSEY.

TURBINE.

1,035,142.

Specification of Letters Patent.

Patented Aug. 13, 1912.

Application filed December 27, 1911. Serial No. 668,036.

To all whom it may concern:

Be it known that I, OTTO BANNER, a subject of the German Emperor, and resident of Easton, in the county of Northampton and

5 State of Pennsylvania, have invented a new and useful Improvement in Turbine-Engines, of which the following is a specification.

This invention consists of a double flow 10 mixed pressure turbine engine of the so-called action or velocity type in which the shaft may be driven by high pressure or low pressure motive fluid or by a combination of the two, the high pressure fluid passing 15 through the two high pressure elements and the two low pressure elements in opposite directions to a central outlet chamber and the low pressure fluid passing through the two low pressure elements in the opposite 20 direction to a central outlet chamber, means being provided whereby the admission of motive fluid is independently controlled to the several low and high pressure inlet chambers.

25 A practical embodiment of my invention is represented in the accompanying drawing, which shows a turbine engine half in side elevation and half in longitudinal central vertical section with my invention applied thereto.

The shaft is denoted by 1, the low pressure blade wheels by 2 and the high pressure blade wheels by 3.

Each low pressure blade wheel is shown 35 as provided with a single row of blades 4 and each high pressure blade wheel is shown as provided with a single row of blades 5.

The partitions in the low pressure elements are denoted by 6 and their nozzles by 40 7. The partitions in the high pressure elements are denoted by 8 and their nozzles by 9.

A common outlet chamber 10 is provided. Upon opposite sides of this outlet chamber 45 I provide the two low pressure elements and beyond these elements I provide low pressure inlet chambers 11 and 12 communicating with their inlets 13, 14. Valves 15, 16, serve to control the admission of the motive 50 fluid under low pressure to these inlet chambers 11 and 12. Beyond these low pressure inlet chambers 11 and 12 are located the two high pressure elements and beyond these high pressure elements I provide the high 55 pressure inlet chambers 17, 18, communicat-

ing with their inlets 19, 20. The admission of motive fluid under the high pressure inlet chambers 17 and 18 is independently controlled by valves 21, 22.

The casing may be divided transversely 60 vertically and also in a horizontal plane coincident with the axis of the shaft 1 to form upper and lower half end members 23, 24, 25, 26, half cylinder members 27, 28, 29, 30, and half divided ring members 31, 32, 33, 34. The lower half cylinder members 28, 30, may be provided with brackets 35, 36, for use in supporting the engine.

The bearings for the shaft 1 at the opposite ends of the casing may be divided in a 70 horizontal plane coincident with the axis of the shaft 1 to form upper and lower half sections 37, 38, 39, 40.

While I have shown the two low pressure elements as each comprising four stages 71 and the two high pressure elements as each comprising two stages and have shown single rows of blades, it is to be understood that the number of stages and the number of rows of blades may be varied to suit 80 different requirements.

It will be seen that the parts are so arranged that the shaft may be driven by admitting the low pressure fluid to either one or both of the low pressure elements or by 81 supplying high pressure fluid to one or both of the high pressure elements or by any combination of these several supplies to suit different requirements.

What I claim is:—

90 1. A mixed pressure turbine engine having two pairs of inlet chambers and an intermediate outlet chamber common to all the inlet chambers.

2. A mixed pressure turbine engine of 91 the velocity type having two pairs of inlet chambers and an intermediate outlet chamber common to all the inlet chambers.

3. A mixed pressure turbine engine having two low pressure inlet chambers, two 10 high pressure inlet chambers and an intermediate outlet chamber common to the high and low pressure inlet chambers.

4. A mixed pressure turbine engine of the velocity type having two low pressure inlet 11 chambers, two high pressure inlet chambers and an intermediate outlet chamber common to the high and low pressure inlet chambers.

5. A mixed pressure turbine engine having two low pressure inlet chambers, two 12

high pressure inlet chambers, an intermediate outlet chamber common to the high and low pressure inlet chambers, and means for independently controlling the admission of the motive fluid to the high and low pressure inlet chambers.

6. A mixed pressure turbine engine of the velocity type having two low pressure inlet chambers, two high pressure inlet chambers, an intermediate outlet chamber common to the high and low pressure inlet chambers, and means for independently controlling the admission of the motive fluid to the high and low pressure inlet chambers.

15 7. A mixed pressure turbine engine having two low pressure inlet chambers, two high pressure inlet chambers beyond the low pressure inlet chambers and a common intermediate outlet chamber.

20 8. A mixed pressure turbine engine of the velocity type having two low pressure inlet chambers, two high pressure inlet chambers beyond the low pressure inlet chambers and a common intermediate outlet chamber.

25 9. A mixed pressure turbine engine having two low pressure inlet chambers, two high pressure inlet chambers beyond the low pressure inlet chambers, a common intermediate outlet chamber, and means for independently controlling the admission of the motive fluid to the high and low pressure inlet chambers.

30 10. A mixed pressure turbine engine of the velocity type having two low pressure inlet chambers, two high pressure inlet chambers beyond the low pressure inlet chambers, a common intermediate outlet chamber, and means for independently controlling the admission of the motive fluid to the high and low pressure inlet chambers.

35 11. A mixed pressure turbine engine having two low pressure elements with inlet chambers beyond them, two high pressure elements and their inlet chambers located beyond the low pressure inlet chambers and a common outlet chamber located between the two low pressure elements.

40 12. A mixed pressure turbine engine of the velocity type having two low pressure elements with inlet chambers beyond them, two high pressure elements and their inlet chambers located beyond the low pressure inlet chambers and a common outlet chamber.

ber located between the two low pressure elements.

55

13. A mixed pressure turbine engine having two low pressure elements with inlet chambers beyond them, two high pressure elements and their inlet chambers located beyond the low pressure inlet chambers, a common outlet chamber located between the two low pressure elements, and means for independently controlling the admission of the motive fluid to the high and low pressure inlet chambers.

65

14. A mixed pressure turbine engine of the velocity type having two low pressure elements with inlet chambers beyond them, two high pressure elements and their inlet chambers located beyond the low pressure inlet chambers, a common outlet chamber located between the two low pressure elements, and means for independently controlling the admission of the motive fluid to the high and low pressure inlet chambers.

75

15. A mixed pressure turbine engine including a casing divided transversely vertically into end inlet members containing the high pressure inlet chambers, cylinder members containing the low pressure inlet chambers and a ring member including the common intermediate outlet chamber.

80

16. A mixed pressure turbine engine including a casing divided transversely vertically into end inlet members containing the high pressure inlet chambers, cylinder members containing the low pressure inlet chambers and a divided ring member including the common intermediate outlet chamber.

85

17. A mixed pressure turbine engine including a casing divided longitudinally and transversely into sectional end members containing the high pressure inlet chambers, sectional cylinder members containing the low pressure inlet chambers and a sectional ring member containing a common intermediate outlet chamber.

90

95

In testimony, that I claim the foregoing as my invention, I have signed my name in presence of two witnesses, this 23 day of Dec. 1911.

OTTO BANNER.
